UNITED STATES PATENT OFFICE.

ELMER L. BRIGGS, OF PLYMOUTH, MASSACHUSETTS.

SHOE FASTENER.

Application filed July 25, 1923. Serial No. 653,689.

To all whom it may concern:

Be it known that I, ELMER L. BRIGGS, a citizen of the United States, residing at Plymouth, in the county of Plymouth and State of Massachusetts, have invented new and useful Improvements in Shoe Fasteners, of which the following is a specification.

This invention relates to shoe fasteners. Its object is to provide a shoe of improved construction which will smoothly fit the foot and yet be yielding and elastic and uniformly supporting to the parts, and be conveniently and quickly laced or fastened. Another object of my invention is to provide a shoe adaptable to athletic wear, containing an elastic fastening edge to the upper, permitting the wearer freedom of muscular action and avoiding the binding effect of strings, eyelets or other unyielding fastenings. In golf, tennis or track shoes, strings frequently break or become loosened and inconvenience to the wearer or failure to win is thereby occasioned.

Another object of my invention is to provide a shoe fastener for infants' shoes which is elastic for bulky foot covering and one which may be quickly secured to the foot. Another object of my invention is to provide a shoe for stout, obese or aged persons, the closing or fastening of which may be so speedily accomplished as to minimize bodily discomfort. Another object of my invention is to provide a shoe fastener convenient to wearers having a disabled arm in that with the remaining one the shoe may be speedily, conveniently and comfortably laced or fastened.

I accomplish the foregoing objects by means of a construction employing an elastic material preferably embodying a rubber compound attached to and forming the adjacent fastening edges of the frontal opening of the shoe. In securing the ease, comfort and support for the foot, ankle and leg of the wearer, the ordinary eyelets and shoe strings may be employed, but in addition to obtain celerity and security in fastening the shoe, I prefer to use, in combination with the elastic material forming the fastening edge, a form of hookless separable fastener known to that art, preferably that shown and described in the Letters Patent No. 1,219,881 issued to Gideon Sundback, dated March 20, 1917. Reference is made in this patent to the use of the device on shoes and apparel, but I have found that it is operative and

practical only where the edges to be brought together may be closed without undue resultant strain, whereas my invention makes it applicable to shoes generally,—the elastic edge obviating the undue strain in tight fitting as well as loose fitting shoes and over-shoes. It is well known that the fastening edges and frontal openings of shoes vary in width and shape, and are not adapted to the shape of the feet of different wearers, and I have discovered that by the use of an elastic fastening edge with such fasteners the strain of closing the shoe will be uniformly and largely eliminated, and will result in snugly fitting and at the same time comfortable footwear.

I accomplish this as shown in the accompanying drawing, in which Fig. 1 is a detailed plan view of a portion of the upper of a shoe partially fastened, and embodying my improvement used in combination with the hookless separable fastener hereinbefore referred to.

Fig. 2 is a transverse section taken on line 2—2 in Fig. 1. Fig. 3 is a detailed plan view of a portion of a rubber webbing strip adapted to form one of the fastening edges of the frontal opening of a shoe and adapted to use with a hookless fastener. Fig. 4 is a transverse section of Fig. 3 taken on the line 4—4. Fig. 5 is a modification showing a detailed plan view of a combination of tape and elastic material constituting a strip or stringer adapted to form one of the fastening edges of the frontal opening of a shoe, and adapted to use with a hookless fastener. Fig. 6 is a transverse section of Fig. 5 taken on the line 6—6.

The same reference numbers indicate corresponding parts in all the figures.

7 is the upper of a shoe, showing the frontal opening 8 partly closed by means of the hookless separable fastener 9, integral with the elastic fabric 10, being mounted on a rib 100 or bead 11 formed thereon. The hookless fastener 9 is stopped at the lower end by the anchor 13, and divides upwardly therefrom, spreading to allow the easy introduction of the foot into the shoe.

In a modified form the bead 11 is attached to the tape or stringer 14, which in turn has fast thereto the elastic fabric 15. This tape is preferably narrow and I find that greater elasticity is shown if the elastic fabric is cut on a bias. I then attach this elastic fabric 15 to the frontal fastening edges of the open-

ing in the shoe, having the anchor 13 fastened to the bottom of the opening, but outside of the tongue, if one is used. The wearer, in both my preferred form and my modified form, by drawing upwardly the closing device of the hookless fastener, closes the opening and secures the shoe to the foot, the elasticity of the edges permitting the contiguous edges of the fastener to meet without undue strain, or attendant discomfort to the wearer.

While my invention is described for use in boots and shoes of all kinds, I do not limit it thereto, as it may be useful in other articles where it is desirable to fasten together two edges of material under tension.

What I claim and desire to secure by Letters Patent is:

1. An article of wearing apparel provided with an opening, the opposite edges of said

opening being composed of elastic material, fastening members on said elastic material on opposite edges of said opening and a member slideable longitudinally of said opening and adapted to bring said fastening members into interlocking engagement with each other.

2. An article of wearing apparel provided with an opening, the opposite edges of said opening being composed of rubber fabric, fastening members on said rubber fabric on opposite edges of said opening and a member slideable longitudinally of said opening and adapted to bring said fastening members into interlocking engagement with each other.

In testimony whereof I have hereunto set my hand this twenty-third day of July, 1923.

ELMER L. BRIGGS.
